UNITED STATES PATENT OFFICE.

JOHN A. DOERFER, OF PORTLAND, OREGON.

VENDING DEVICE.

1,315,014.

Specification of Letters Patent. Patented Sept. 2, 1919.

Application filed October 25, 1917. Serial No. 198,551.

To all whom it may concern:

Be it known that I, JOHN A. DOERFER, a citizen of the United States, residing at Portland, State of Oregon, have invented 5 certain new and useful Improvements in Vending Devices, of which the following is a specification.

My invention relates to vending devices in general, and particularly to that class 10 of such devices as are used for dispensing measured quantities of liquids, it being especially adapted for use in dispensing gasolene at automobile filling stations, and is so illustrated in the accompanying drawings, which form a part of this application 15 for Letters Patent.

The objects of my invention are to provide a device that will, upon the insertion therein of a coin, automatically dispense a measured 20 amount of a liquid; to provide a device that can be set to dispense whole and fractional measures (as gallons and fractions thereof) according to the amount of liquid called for by the inserted coin at prevailing prices; 25 and to provide such a device in a simple, compact, cheap and reliable form of construction.

I accomplish the above objects and other 30 desirable results by means of the construction illustrated in the accompanying drawings, like characters of reference indicating like parts throughout the several views thereof, and in which:—

Figure 1 is a side elevation of my device, the casing being broken away to best illustrate the construction.

Fig. 2 is a plan view of my device, parts being broken away to best illustrate the construction.

Fig. 3 is a diagrammatical perspective view of the coin actuated levers.

Fig. 4 is a diagrammatical perspective view of the whole measure latch.

Fig. 5 is a plan view of the fractional 45 measure device assembled, certain parts being broken away for illustration.

Fig. 6 is an elevation of the gear and ratchet operating the fractional measure device.

In general my invention comprises, first 50 a plurality of slots and levers corresponding respectively to coins of various denominations; second means whereby either of said levers independently may simultaneously close a switch and thus start a motor, and also put the fractional measure device into

operating position; third, means whereby said motor may be allowed to attain a pre-determined speed and then place a pump plunger into operation; fourth, means 60 whereby said pump plunger may make a predetermined number of complete strokes and then a fractional stroke governed by said fractional measure device; and fifth, means whereby at the completion of said 65 fractional stroke of the plunger said fractional measure device may open said switch and release said coin operated levers to return to their initial position.

In order that coins of various denominations may start the mechanism I provide a plurality of coin slots 7, 8, 9, 10 and 11, into which the suitable coin is placed, each of said slots being adapted to receive only its respective coin, as nickles, dimes, quarters, etc.

Corresponding to each slot is a hand rod 12, which, upon being pushed closes the lower end of its respective slot, and which is held in its initial position by a spring 13, as shown in Fig. 1.

In alignment with each of said hand rods 12 is a corresponding push rod 14, each of said rods 14 starting at the innermost edge of its respective coin slot and therefrom extending inwardly, a spring 15 being adapted to hold the rod 14 in its initial position, as shown in Fig. 1.

When said rods 14 and hand rods 12 are each in their initial positions there is a 90 space intermediate the respective ends thereof, said space registering with the lower end of the respective coin slot, so that an inserted coin slides down the slot and comes to rest upon its face intermediate said hand rod 12 and said push rod 14, the coin thus forming an operative member between the hand rod 12 and the push rod 14, whereby a push upon said hand rod will operate said push rod.

Each of said rods 14 is connected by links 16 to a switch blade 17.

As shown in the drawings there is a switch for each of said rods 14, but it is evident to one skilled in the art that the 105 several rods may be arranged to operate the same switch if desired.

The switch is closed by the operation of the rod through the agency of the inserted coin, and thus the electric motor 18 is 110 started.

Upon each of rods 14 is a cam 19 which

coöperates with a latch 20, said cam holding said latch open until the movement of the rod 14 has accomplished the closing of the switch, whereupon said latch engages the 5 end of said cam and thus holds the rod 14 securely in place with the switch closed, against the action of spring 15.

The motor 18, being thus set in motion will operate a governor 21 by means of 10 bevel gears 22, shaft 23 and the spur gears 24, as shown in Fig. 1.

When governor 21 has attained a predetermined speed it will lower stem 25, thereby releasing lever 26, which has been resting 15 upon the upper end of the stem 25, as shown in Fig. 1.

Lever 26 will then be caused to drop by weight 27 thereon, and by means of shaft 28 and arms 29 thereon will engage the two 20 members of clutch 30.

One member of clutch 30 is slidable but not rotatable upon motor shaft 31, and co-acts with arms 29 to be longitudinally moved thereby upon said shaft 31.

25 The other member of clutch 30 is secured to a worm 32 rotatably mounted upon shaft 31, as shown in Figs. 1 and 2.

Said worm 32 meshes with a worm gear 33, which gear also meshes with rack teeth 30 upon pump plunger 34, as shown in Fig. 1.

By this mechanism the pump is not started until the motor has attained a predetermined speed, regulated by the governor, thereby overcoming the losses of dispensed 35 liquid incident to the slow movement of the pump plunger when starting.

In order that an exact measure of liquid may be delivered by one stroke of said pump plunger I mount thereon a pin 35 which will 40 contact with lever 26, and by raising said lever will release clutch 30 when the proper measure of liquid has been delivered.

Lever 26 when thus raised enters and is held by a latch 36, shown in detail in Fig. 4. 45 Said latch consists of forks 37 between which lever 26 enters, and a tongue 38 which is forced outward by the entering lever 26 and is then returned beneath said lever by the weight of reach rod 39 upon bell crank 50 40 which coöperates with latch 38, as shown in Fig. 4.

When clutch 30 is thus disengaged upon the completion of the stroke of pump plunger 34, said plunger is returned to its 55 initial position by means of weight 41 attached to cord 42, which cord is wound upon the hub of gear 43 which meshes with rack teeth upon pump plunger 34, as shown in Figs. 1 and 2.

60 When plunger 34 returns to its initial position pin 35 contacts with lever 44 thereby withdrawing tongue 38 and releasing lever 26 from latch 36, thus reengaging clutch 30 which then causes plunger 34 to make another stroke.

The above described cycle of operations continues indefinitely until stopped by the fractional measure device to be hereinafter described.

Each catch 20 is in the form of a bell 70 crank, one arm of which forms the catch proper, and the other arm of which is pivotally attached to a corresponding rod 46, which rods are slidably mounted in bearings 47 and 48, as shown in Figs. 1, 2 and 3. 75

Mounted upon each of rods 46 is a collar 49, and intermediate said collar and bearing 47 is a spring 50, for the purpose of keeping its respective rod in its initial position with the catch 20 in contact with its respective 80 cam 19, as shown in Fig. 1.

Each of rods 46 has fixed upon the end thereof opposite said catch 20, a wedge shaped contact piece 51, as shown in Figs. 1 and 3.

A clutch shifter 52 is pivotally mounted at 53, one arm of which engages a peripheral groove 54 in one end of a sleeve 55 freely mounted upon a shaft 56, as shown in Figs. 1 and 2, and in detail in Figs. 3 and 5. 85

Pivottally mounted upon the opposite arm of shifter 52 is a plurality of connecting rods 57, there being as many of said rods as there are coin slots.

The opposite end of each of said connecting rods 57 is slotted to engage with a pin 58 mounted upon the respective collar 49, as shown in Figs. 1 and 2, and in detail in Fig. 3. 95

Upon that end of sleeve 55 opposite 100 groove 54 is one member of a clutch 59, the other member of said clutch being secured to shaft 56, as shown in Fig. 5, and intermediate said clutch members is a spring 60 adapted to keep said clutch members initially out of contact. 105

When a coin has been inserted in the respective slot and the respective rod 14 has been moved so that cam 19 has passed over catch 20, the spring 50 will cause rod 46 to 110 move toward shaft 56, thereby causing catch 20 to engage the end of cam 19, thus holding rod 14 in its advanced position against spring 15, and with the switch 17 closed.

By means of its respective pin 58 and connecting rod 57 the movement of one of rods 46 by its respective spring 50 causes clutch shifter 52 to move, thereby engaging the members of clutch 59. 115

The movement of clutch shifter 52 by any 120 one of connecting rods 57 causes all the other connecting rods to move in unison therewith, which they are allowed to do without moving their respective rods 46 by means of slots 61 in said connecting rods 57, as 125 shown in detail in Fig. 3.

The engagement of clutch members 59 is thus accomplished by mechanisms independently operated through the agency of the coin inserted, which coin becomes temporar- 130

ily a member of the operating mechanism, and the wedge or contact piece 51 corresponding to said coin is moved toward shaft 56 and held in such moved position by its respective spring 50, all the other contact pieces remaining in their initial positions.

When the coin has performed its function as a temporary member of the operating mechanism, it is released by the return 10 movement of hand rods 12, and falls into coin box 62, shown in Figs. 1 and 2.

The engagement of clutch members 59 secures sleeve 55 upon shaft 56, which shaft is rotated in the direction of the arrows.

15 To rotate shaft 56 I provide a gear 63 freely mounted thereon and meshing with a change gear 64.

Said change gear 64 meshes with a gear upon shaft 65, upon the opposite end of 20 which is a gear 66 meshing with the rack teeth upon pump plunger 34.

By this train of gears the upward movement of plunger 34 rotates gear 63 according to the arrows shown on shaft 56, and said 25 shaft is also rotated by ratchet teeth 67 within gear 63 engaging dogs 68 upon flange 69 which is secured to shaft 56, as shown in detail in Figs. 5 and 6.

When plunger 34 moves downward said 30 ratchet arrangement allows gear 63 to turn backward without rotating shaft 56.

Secured to sleeve 55 are a plurality of arms 70, there being one of said arms to correspond respectively to each coin slot and 35 contact piece 51, and said arms have various angular relations one with another, as shown in Fig. 1, and in detail in Fig. 5.

Rotatably mounted upon each of said arms is a roller 71 adapted to contact with 40 its respective contact piece 51, as the sleeve 55 and arms 70 rotate.

As has been previously described, the sleeve 55 is operated from the plunger 34, and the angular position of the various arms 45 70 upon said sleeve together with the gear ratio between plunger 34 and gear 63 is such that when the exact amount of liquid called for by the coin inserted has been delivered, the respective roller 71 will contact with its 50 contact piece 51 and force the same away from the shaft 56, thereby releasing catch 20 and allowing rod 14 to return to its initial position and open the switch 17, thus stopping the motor 18 and bringing the entire 55 mechanism to rest.

When rod 14 returns to its initial position pin 58 moves to that end of slot 61 farther removed from shaft 56 which frees rod 57 and shifter 52, and allows spring 60 to dis- 60 engage the members of clutch 59.

Sleeve 55 is then free upon shaft 56 and is returned to its initial position by means of weight 72 hung from a cord 73 which operates upon a sheave 74 secured to sleeve 55, 65 as shown in Fig. 1.

An arm 75 upon that member of clutch 59 which is secured to sleeve 55 contacts with a stationary rest 76 when said sleeve has returned to its initial position.

The governor 21 then causes rod 25 to rise 70 and lift lever 26, and thus disengage the members of clutch 30, whereupon weight 41 causes plunger 34 to lower into its initial position, when the mechanism is set for another operation upon the insertion of a coin. 75

By means of this mechanism the plunger 34 will make several strokes while the sleeve 55 is making a partial revolution, and the plunger will be stopped when the proper roller 71 contacts with its respective contact 80 piece 51, which latter was moved toward shaft 56 into a position for contact with roller 71, as shown in dotted lines in Fig. 1, by the operation of hand rod 12 after inserting the coin in its proper slot. 85

The gear 66 may be made of such a size as to allow the plunger 34 to make as many full strokes as desired and then any fraction of a stroke before being stopped as above described, and thus, by simply changing the gear 66 the mechanism may be set to compensate for the fluctuation in price of the liquid being dispensed, so that the amount delivered always exactly corresponds in value to the coin inserted. 95

My invention may be made of any size and constructed of any materials deemed convenient and suitable for a device of this character, and while I have illustrated and described a form of construction and arrangement of parts found desirable when materializing my invention, I wish to include in this application for Letters Patent all mechanical equivalents and substitutes that may fairly be considered to come within the scope and purview of my invention as defined in the appended claims. 100

Having described my invention so that others skilled in the art may be enabled to construct and use the same, what I claim as 110 new and desire to secure by Letters Patent is:—

1. In a device for vending liquids; a motor; a governor; a pump plunger; means whereby said governor will connect said motor to said plunger when said motor has attained a predetermined speed. 115

2. In a device for vending liquids; a pump plunger; a motor; means whereby said pump plunger may be automatically connected to 120 said motor when the latter has attained a predetermined speed; and means whereby said plunger may be automatically disconnected from said motor when said plunger has completed a predetermined number of 125 strokes and fraction thereof.

3. In a device for vending liquids; a motor; coin controlled means for starting said motor; a pump plunger; means whereby said motor may be connected to said plunger 130

when the former has attained a predetermined speed; means whereby the said plunger may be automatically disconnected from said motor when said plunger has completed 5 a predetermined number of strokes and fraction thereof; and means whereby said motor may be automatically stopped when said plunger is thus disconnected.

4. In a device for vending liquids; a motor; coin controlled means for starting said motor; a pump plunger; a gear train intermediate said motor and said plunger; a clutch intermediate said gear train and said motor; a governor controlling the speed 10 of said motor; means whereby said governor may engage said clutch when said governor attains a predetermined speed; means whereby said plunger may disengage said clutch upon the completion of each stroke of 15 said plunger; and means to return said plunger to its initial position upon the release thereby of said clutch.

5. In a device for vending liquids; a motor; coin controlled means for starting said 20 motor; a governor connected to said motor; a train of gears intermediate said plunger and said motor adapted to operate said plunger from said motor; a clutch connecting said gear train to said motor; a lever operating said clutch; a member intermediate 25 said lever and said governor whereby said governor regulates and determines the position of said lever; means whereby said plunger may disconnect said lever from said 30 member, and move the former to disconnect said clutch; a latch to hold said lever after the same has been moved by said plunger; means to return said plunger to its initial 35 position after said clutch has been released thereby; and means to release said lever from said latch when said plunger arrives 40 at its initial position.

6. In a device for vending liquids; a motor; a pump plunger; a gear train intermediate 45 said motor and said plunger; a clutch in said gear train; a governor; means whereby said governor may engage said clutch; means whereby said plunger may disengage said clutch at the completion of 50 one stroke of said plunger; means to return said plunger to its initial position; means to

retain said clutch disengaged and uninfluenced by said governor while said plunger is returning to its initial position; and means to reestablish connection between said 55 clutch and said governor when said plunger arrives at its initial position.

7. In a vending device; a plurality of coin controlled push rods; a catch for each of 60 said rods; a plurality of push rods, each operating one of said catches; a measuring device; a clutch operating said measuring device; a clutch shifter; a plurality of reach rods, all pivotally connected to said clutch shifter and each slidably connected to its 65 respective one of the last mentioned push rods.

8. In a vending device; a motor; a coin controlled motor starting device; a latch to retain said device in operating position; a 70 rotary member; arms secured to said member; contact pieces corresponding to each of said arms; means whereby when a predetermined amount of material has been delivered a certain one of said arms will contact with 75 its respective contact piece; and means whereby said contact piece will operate said latch to release said motor starting device.

9. In a device for vending liquids; a pump plunger; a shaft; means to rotate said shaft 80 from said plunger; a member freely mounted upon said shaft; arms secured to said member; a clutch to secure said member upon said shaft; coin controlled means to simultaneously operate said plunger and 85 said clutch; contact pieces coöoperating with said arms; means whereby contact of one of said arms with its respective contact piece will stop said plunger and release said clutch; means to return said plunger to its 90 initial position; and means to return said freely mounted member to its initial position.

In witness whereof I claim the foregoing as my own, I hereunto affix my signature in 95 the presence of two subscribing witnesses, at Kent, county of Sherman, State of Oregon, this 29 day of August, 1917.

JOHN A. DOERFER.

Witnesses:

FRED HAYNES,
HENRY SCHADEWITZ.
